A. Bernie Wood, 721 E. Davis St.,
Arlington Heights, Ill. 60005

Filed Mar. 18, 1966, Ser. No. 1,530

Term of patent 14 years

(Cl. D58—12)

FIG. 2 is an end elevation thereof on an enlarged scale.

FIG. 3 is a side elevation thereof, and

FIG. 4 is a top elevational view thereof.

The sides opposite to those shown in FIGS. 1 and 3 are of the same appearance as that shown in these figures.

I claim:

The ornamental design for a candy box, as shown and described.
